[57] CLAIM

The ornamental design for a diver's buoyancy compensator backpack support, as shown and described.

DESCRIPTION

FIG. 1 is a perspective view of a diver's buoyancy compensator backpack support showing our new design;

FIG. 2 is a left side elevational view thereof;

FIG. 3 is a rear elevational view thereof;

FIG. 4 is a bottom plan view thereof; and
FIG. 5 is a perspective view, the broken line showing of
a diver's jacket is for illustrative purposes only and
forms no part of the claimed design.
